SOLENOID

Theodore A. Wetzel, Milwaukee, Wis., assignor to
Milwaukee Gas Specialty Company, Milwaukee, Wis., a corporation of Wisconsin

Application August 28, 1937, Serial No. 161,421

8 Claims. (CL 175—338)

This invention relates to electromagnets and refers particularly to the solenoid type of electromagnet designed to operate valves and kindred appliances.

The attainment of quietness in operation has always been a problem, particularly where the solenoid is of the single phase alternating current type. The constructions heretofore proposed for this purpose have been objectionable from the standpoint of requiring an excessive number of parts, and also for the reason that they did not provide against noise resulting from lateral motion of the armature.

It is therefore an object of this invention to provide quiet operation for a solenoid of the character described with a minimum number of parts.

Another object of this invention resides in the provision of means whereby lateral play between the armature and its guideway is positively taken up to preclude noise arising from this cause.

Another object of this invention is to provide means whereby the shading ring on the armature splits the phase of the magnetic flux to further guard against chattering.

Another object of this invention is to provide a construction whereby the effects of residual magnetism in the armature are vitiated to preclude the armature being held against its normal motion consequent to the deenergization of the magnet coil.

A further object of this invention is to provide a solenoid which is particularly applicable for use with valves, and especially gas valves.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawing illustrates one complete example of the physical embodiment of the invention constructed according to the best mode so far devised for the practical application of the principles thereof, and in which:

Figure 1 is a longitudinal sectional view through a valve equipped with the solenoid of this invention illustrating the same in its deenergized condition;

Figure 2 is a longitudinal sectional view through the armature per se;

Figure 3 is a cross sectional view through the

armature taken on the plane of the line 3—3 of Figure 2; and

Figures 4 and 5 are enlarged sectional views through the armature and its guide tube illustrating the manner in which its unbalanced mass on a transverse plane causes the magnetic pull of the coil to hold the same against one side of the tube.

Referring now particularly to the accompanying drawing in which like numerals indicate like parts, the numeral 5 designates a guide tube of non-magnetic material closed at its upper end by a plug 6 of magnetic metal and having a plunger type armature 7 slidable therein. A magnet coil 8 surrounds the upper end portion 15 of the tube 5, which, upon energization, draws the armature upwardly toward the plug 6.

The upward attraction imposed on the armature upon energization of the coil is augmented by a magnetic sleeve 5' which surrounds the upper end of the tube 5; and to further improve the efficiency of the solenoid and reduce the wattage consumption, an iron shell is attached to the sleeve 5' and encloses the coil with its lower end in contact with an iron washer 18'. Hence, upon energization of the coil 8 the flux flows through the shell and the washer, which, lying close to the armature, provides a short path to the armature and thus reduces the wattage required to lift the armature.

In the present instance where the solenoid is used with a gas valve, the upward motion of the armature lifts a valve 9 off its seat, the seat being located between the inlet and outlet of the valve body 11.

Being closed at its upper end, the guide tube 5 serves as a sealing tube to preclude leakage from the valve body. It is conveniently fitted into a cover 10 which closes the open top of the valve body. The cover 10 is held in place by a clamping ring 12 threaded to the body and engaged over a plate 13 fixed to the underside of the cover. The same screws which hold the plate 13 to the underside of the cover also fasten the magnetic washer 10' to the cover.

The valve 9 comprises a valve disc having a leather face 14 loosely secured to the lower end of a non-magnetic stem 15 which is slidably received in a bore 16 extending longitudinally through the center of the armature. The stem 15 is longer than the armature and has a non-magnetic head 17 on its upper end to be engaged by the upper end of the armature with a hammer-like blow upon response of the armature to energization of the coil.

A recess 18 in the undersurface of the magnetic plug 6 accommodates the head 17 of the valve stem and permits the armature to engage the lower edge of a non-magnetic spacer collar 19 secured in the recess 18. The spacer projects down below the bottom of the plug 6 to hold the armature from actual contact with the plug and thereby preclude residual magnetism of the armature from holding the valve open after de-
energization of the coil.

As best shown in Figures 4 and 5, the armature consists substantially of a cylinder of magnetic metal having a plurality of longitudinal flutes or grooves 20 cut therein at spaced intervals extending partially around the circumference of the cylinder. These flutes or grooves form the cross section of the armature into a small diameter cylinder having a plurality of radial circumferentially spaced ribs 21 extending longitudinally throughout the length thereof with a portion 22 of substantial mass disposed at one side of the axis of the armature.

This unbalanced or eccentric distribution of the mass in the plunger gives the same a low magnetic reluctance at its side having the portion 22 so that upon energization of the coil the armature not only rises to enter the enclosure defined by the magnetic sleeve 5', but is also drawn sidewise to be held against the inner surface of the guide tube 5 and thus preclude the armature from wandering and rattling in its guide tube.

Near its upper end the armature is encircled by a shading ring 23 of copper or other suitable metal. It appears possible that the shading ring, being positioned as it is, aids the magnet coil in maintaining the armature tightly against the spacer collar 19.

Four factors of the construction as described thus coact to produce an efficient and quiet solenoid. They are—the magnetically unbalanced armature; the shading ring carried by the armature; the magnetic sleeve; and the magnetic plug at the upper end of the guide tube. The magnetic sleeve extends down into the coil a substantial distance so that a considerable part of the armature is telescoped into it, thus giving the magnetically unbalanced formation of the armature maximum effectiveness.

The shading ring, being located where it is, also serves to split the phase of the magnetic flux. This follows from the fact that when the armature is in its raised position, the shading ring lies within the confines of the sleeve 5'. The flux flowing from the sleeve 5' to the armature is thus split by the presence of the shading ring causing a part thereof to lag behind the rest. The advantages of multi-phase current are thus achieved to a degree.

From the foregoing description taken in connection with the accompanying drawing, it will be readily apparent to those skilled in the art that this invention provides a solenoid of greatly improved construction, particularly with respect to those factors which determine quietness of operation.

What I claim as my invention is:

1. A plunger type armature for electromagnets comprising: substantially a cylinder of magnetic material having circumferentially spaced longitudinal ribs projecting radially therefrom, one of said ribs having a substantially greater width than the others so as to provide an unbalanced mass on a transverse plane whereby one side

of the plunger has a lesser magnetic reluctance than other portions thereof.

2. A solenoid comprising: a coil; guide means disposed within the coil; a rigid armature movable within the coil and snugly but slidably engaging said guide means, said armature having both its ends lying in planes substantially normal to the central longitudinal axis of the armature and having its magnetic mass unsymmetrically distributed with respect to said axis with considerably greater magnetic mass on one side of a plane parallel to the line of motion of the armature and including the axis of the coil than on the opposite side thereof so that the magnetic reluctance at one side of the armature is greater than at other portions thereof; and stationary magnetic means alongside the armature and cooperating therewith whereby the armature is held laterally against the guide means upon energization of the coil.

3. A plunger type armature for electromagnets comprising: substantially a cylinder of magnetic metal having a plurality of longitudinal flutes to give the plunger a ribbed cross sectional shape, said flutes being so circumferentially spaced that at least one of the ribs is substantially wider than the rest so that the plunger has greater mass at one side of its axis than at the opposite side to provide a path of lesser reluctance at said first side of the plunger.

4. A solenoid construction of the character described comprising: a tube of non-magnetic metal; a magnet coil surrounding the tube; a magnetic sleeve surrounding the tube within one end portion of the coil; a plunger type armature slidable in the tube, said armature having guide ribs extending radially therefrom for contact with the inner wall of the tube and having a portion of substantial mass and considerably wider than the guide ribs disposed at one side of its axis to provide a path of low magnetic reluctance so that upon energization of the coil the magnetic pull exerted through the magnetic sleeve holds the armature against the inside surface of the tube.

5. A solenoid construction of the character described comprising: a tube of non-magnetic material; a magnet coil surrounding one end portion of the tube; a magnetic sleeve surrounding the tube within one end portion of the coil; a plug closing said end of the tube and formed of magnetic metal; a plunger type armature slidable in the tube toward the magnetic plug and into the magnetic sleeve upon energization of the coil, said armature having circumferentially spaced longitudinally extending ribs projecting radially therefrom, one of said ribs having a substantially greater width than the others so as to provide a portion of substantial mass at one side of the axis of the armature whereby said side of the armature has lesser magnetic reluctance than other portions thereof so that the armature is drawn firmly against the inside surface of the tube by the magnetic pull exerted through the magnetic sleeve upon energization of the coil; non-magnetic spacer means for holding the armature out of contact with the magnetic plug; and a shading ring encircling the armature near its end which moves into the magnetic sleeve.

6. A solenoid comprising: a magnet coil; a rigid armature; guide means to limit the motion of the armature substantially to movement axially of the coil; a stop against which the armature is moved upon energization of the coil; a magnetic sleeve within one end portion of the coil,

5 said magnetic sleeve being shorter than the coil but long enough to receive at least a portion of the armature as it engages said stop; said armature having both its ends lying in planes substantially normal to the central longitudinal axis 10 of the armature and having its magnetic mass unsymmetrically distributed with respect to said axis with considerably greater magnetic mass on one side of a plane parallel to the line of motion 15 of the armature and including the central longitudinal axis of the magnetic sleeve than on the opposite side thereof so that one side of the armature has considerably less magnetic reluctance than other portions thereof; whereby the armature is attracted laterally toward the magnetic sleeve to take up all play between the armature and its guide means.

6 7. A solenoid comprising: a magnet coil; a rigid armature; guide means to limit the motion of 20 the armature substantially to movement axially of the coil; a stop located to be engaged by the armature upon movement thereof in response to energization of the coil; a magnetic sleeve within one end portion of the coil, said magnetic sleeve 25 being shorter than the coil but long enough to receive at least a portion of the armature as it engages the stop, said armature having both its ends lying in planes substantially normal to the central longitudinal axis of the armature and 30 having its magnetic mass unsymmetrically distributed with respect to said axis with considerably greater magnetic mass on one side of a plane parallel to the line of motion of the armature and including the central longitudinal axis of the 35 magnetic sleeve than on the opposite side thereof so that one side of the armature has considerably less magnetic reluctance than other portions thereof whereby the armature is attract-

ed laterally toward the magnetic sleeve to take up all play between the armature and its guide means; and a shading coil encircling that portion of the armature which moves into the magnetic sleeve so as to split the phase of the magnetic flux flowing from the sleeve to the armature. 5

8. A solenoid comprising: a magnet coil; a magnetic sleeve disposed within one end of the coil and spaced from the opposite end thereof; a rigid armature responsive to energization of the 10 coil; a tube in which the armature slides and by which the armature is constrained to motion axially through the coil and into said magnetic sleeve; a magnetic stop within the magnetic sleeve but spaced therefrom for limiting the motion of 15 the armature in response to energization of the coil; non-magnetic means for spacing the armature from said stop, the armature having both its ends lying in planes substantially normal to the central longitudinal axis of the armature and 20 having its magnetic mass unsymmetrically distributed with respect to said axis with considerably greater magnetic mass on one side of a plane parallel to the line of motion of the armature and including the central longitudinal axis of the 25 magnetic sleeve than on the opposite side thereof so that one side of the armature has considerably less magnetic reluctance than other portions thereof whereby the armature is drawn laterally toward the magnetic sleeve to maintain the 30 same in firm engagement with its guide tube; and a shading coil carried by and encircling the armature at a point so spaced from the end of the armature which enters the magnetic sleeve that the shading ring lies between the ends of the 35 magnetic sleeve when the armature contacts its stop.
